United States Patent Office.

JOSHUA BRIGGS, OF PETERBORO, NEW HAMPSHIRE.

Letters Patent No. 71,967, dated December 10, 1867.

IMPROVED PIANO-STOOL.

The Schedule referred to in these Letters Patent and making part of the same.

TO ALL WHOM IT MAY CONCERN:

Be it known that I, JOSHUA BRIGGS, of Peterboro, in the county of Hillsboro, and State of New Hampshire, have invented an Improvement in Piano-Forte Stools; and I do hereby declare that the following, taken in connection with the drawings which accompany and form part of this specification, is a description of my invention sufficient to enable those skilled in the art to practise it.

The invention relates to the construction of piano-forte stools, with reference to combining strength and durability, with provision for separation into parts for the purpose of compacting stools for transportation. United States Letters Patent were granted to me on the 23d of October, 1866, for certain improvements in such stools, and my present improvements have reference to the same general object sought in my previous construction.

The drawings represent a stool embodying my present improvements, A showing the same partly in elevation and partly in section, and B a cross-section on the line *x x*.

a denotes the pillar, mounted on feet or legs, *b*, and receiving the screw-spindle *c*, which is surmounted by the seat *d*. In applying the seat to the spindle, the connection is made through a cap or plate, *e*, which is screwed to the under side of the seat, the spindle and cap being generally permanently connected by a pin or rivet, driven through the hub of the cap, and into or through the spindle, the hub being first driven down over the top of the spindle. This means of connection of the spindle and cap-plate is objectionable, in that it is impossible to take the spindle and cap apart and put them together without the aid of a machinist, and is as impossible to drive the cap down upon the spindle in such manner as to have the seat always stand at right angles to the spindle. To obviate this, I turn the upper end of the spindle to a true cylinder, and bore the hub out correspondingly, or to just fit over the same, and down upon a shoulder on the spindle, and then connect the cap and spindle by a set-screw, in such manner that the spindle may be removed from and applied to the cap at any and all times by ordinary skill, or without the aid of a workman; and this feature constitutes one part of my invention, as will be understood by inspection of the view shown at A, wherein the top, *f*, of the spindle is shown as fitting into the hub or boss *g* of the cap, and as being confined thereto by a set-screw, *h*, which passes through the hub, and into a recess, *i*, made in the side of the spindle, the simple turning back of the screw allowing the spindle to be at any time removed, as will be readily understood. The pillar *a* is made of wood, and the metal nut *k*, in which the spindle turns, is screwed into the top of the pillar, the screw-bolt *l*, by which the pillar is confined to the base, being first dropped through the pillar, all as shown in my patent above referred to. In applying the legs or feet to the base, or in connecting the pillar and feet, I use a metal block or socket-piece, *m*, constructed as follows: The block is made with four or more main sides or faces, (in correspondence with the number of feet,) and in each of these faces I make a recess, *n*, with vertical side lips or flanges, *o*, and a bottom seat, *p*, and form the connecting end of each foot to fit into said recess and rest upon said seat, the lips or flanges *o* fitting over vertical projections, *q*, on the sides of the feet. The top face *r* of the foot comes flush with the top of the block *m*, and the bottom face *s* of the pillar fits down upon and covers all the joints, and holds the feet securely and tightly in place. The block *m* has a broad socket, *t*, at its centre, into which a tail-piece or shank, *u*, on the bottom of the pillar, fits, the bolt *l* passing through this shank and through the bottom piece *v* of the block, the head resting on this bottom piece as a seat, when the nut *w* is screwed up on the bolt and against the bottom surface of the block. To conceal the end of the screw-bolt, I use a centre-piece, *w'*, having a screw-thread fitting upon the bolt-screw, and a recess for containing the bolt-nut, as shown at A. A dowel-pin, *x*, may project up from one or more of the feet into a recess in the bottom of the pillar, to keep the pillar from turning upon the block *m*.

It will thus be seen that the screw-spindle may be readily taken from the seat, the pillar from the block *m*, and the block from the feet, for the purpose of compactly packing them together, and that all may be as readily put together, without other than the most ordinary skill, and that, when thus put together, they are all as firmly and immovably connected, (except as to the proper movement of the seat and screw-spindle, relatively to the pillar and base or the dismemberment of the stool by design,) as they would be were the relative parts of the seat and base made or cast integral, or arranged to have no dismemberment.

I claim, in combination with the pillar and feet, the socket-block *m*, having recesses formed with side lips

or flanges, *o*, to fit into grooves *q* in the feet, and bottom seats, *p*, between which and the shoulder on the pillar the feet are securely confined, substantially as described.

Also, the centre-piece *w'*, fitting upon and covering the screw-bolt and nut which confine the pillar to the base, substantially as shown and described.

Also, constructing the socket-block *m* with a centre socket, *t*, into which the tail-piece of the pillar fits and is confined, substantially as described.

Also, making the screw-spindle removable from the seat, substantially as set forth.

JOSHUA BRIGGS.
